UNITED STATES PATENT OFFICE.

JOHANNES RUTHS, OF DJURSHOLM, AND NILS HEZEKIEL FRENNE, OF STOCKHOLM, SWEDEN, ASSIGNORS TO RUTHS ACCUMULATOR AKTIEBOLAG, OF STOCKHOLM, SWEDEN, A CORPORATION OF SWEDEN.

STATIONARY-STEAM-PLANT RESERVE.

Application filed March 22, 1923, Serial No. 626,937, and in Sweden March 22, 1922.

Our invention relates to stationary steam plants provided with reserve boilers for generating steam when insufficient power is delivered by the normally operating units.

Such reserve boilers must be put into service quickly. To facilitate a quick start such boilers are often maintained filled with water and under fire to keep the water hot. However a boiler can not be well insulated and loses much heat through radiation.

Our invention has for its object to save heat in such a plant while at the same time permitting a rapid starting of reserve boilers by providing a receptacle which is heavily insulated and holds hot water which hot water is conducted to the boiler when it is to be fired up, whereby steam can be raised in a short time and, further, in returning the hot water from the boiler to the receptacle when the boiler is cut out of service, whereby the water is maintained at a high temperature so that it can be used again when the reserve boiler is to be placed in service.

The saving thereby effected is the difference in radiation losses between the well insulated receptacle and the poorly insulated boiler.

The invention is illustrated in the accompanying drawing in which *a* designates a reserve or stand-by boiler which is normally held unfired and empty. *b* designates a receptacle surrounded by an insulating layer *c*, situated above boiler *a* and normally filled with hot water. When the load is too heavy for the main power supply of the plant so that the reserve boiler *a* must be fired up, valve *l* in conduit *k* is opened, valve *f* in conduit *e* being closed, and the steam space of receptacle *b* is connected with boiler *a* whereby steam is evaporated in receptacle *b* and conducted to the boiler. Valve *f* is then opened and hot water flows from receptacle *b* into the boiler. The boiler is then fired in usual manner and coupled in to add power to the remainder of the plant.

When the boiler *a* is again to be cut out

of service, valve *f* or *l* or both are opened and the pressure in boiler *a* forces water into receptacle *b* until the pressure is equal in the two. If preferred, pump *p* is put into operation and valves *f* and *l* closed, whereby water is forced into receptacle *b* until boiler *a* has been emptied or as much has been transferred as desired. Valve *o* permits connection of receptacle *b* with the atmosphere.

What we claim is:

1. In a steam plant, a reserve boiler, a storage receptacle of large capacity adapted to contain sufficient hot water to initially charge said reserve boiler, a conduit connecting the lower portion of said boiler and the lower portion of said receptacle, a valve in said conduit, and means for transferring water from said boiler to said receptacle and from said receptacle to said boiler, as desired. 55

2. In a steam plant, a reserve boiler, a storage receptacle of large capacity located above said reserve boiler and adapted to contain sufficient hot water to initially charge said reserve boiler, a conduit connecting the lower portion of said boiler and the lower portion of said receptacle, a valve in said conduit, means for transferring water from said boiler to said receptacle comprising a pump, and means for transferring water from said receptacle to said boiler. 70

3. In a steam plant, a reserve boiler, a storage receptacle of large capacity adapted to contain sufficient hot water to initially charge said reserve boiler, a conduit connecting the lower portion of said boiler and the lower portion of said receptacle, a conduit connecting said boiler to the upper portion of said receptacle, valves in said conduits, and means for transferring water from said boiler to said receptacle and from said receptacle to said boiler, as desired. 75 80 85

In testimony whereof we affix our signatures.

JOHANNES RUTHS.
NILS HEZEKIEL FRENNE.
